UNITED STATES PATENT OFFICE.

SAMUEL OLSON, OF MILWAUKEE, WISCONSIN.

ROTARY STEAM-ENGINE.

SPECIFICATION forming part of Letters Patent No. 727,677, dated May 12, 1903.

Application filed October 16, 1902. Serial No. 127,363. (No model.)

To all whom it may concern:

Be it known that I, SAMUEL OLSON, a citizen of the United States, and a resident of Milwaukee, in the county of Milwaukee and **5** State of Wisconsin, have invented certain new and useful Improvements in Rotary Steam-Engines; and I do hereby declare that the following is a full, clear, and exact description thereof.

10 The improvements consist in certain peculiarities of construction and combination of parts hereinafter particularly set forth with reference to the accompanying drawings and subsequently claimed, the object of the **15** invention being to provide simple, economical, and efficient compound rotary steam-engines.

Figure 1 of the drawings represents a front elevation of a rotary steam-engine in accordance with my invention, partly in section; **20** Fig. 2, a sectional view of a portion of the engine inverted, this view being indicated by lines 2 2 in the first figure; Fig. 3, a partly-sectional end elevation of said engine, the plane of the section being indicated by line **25** 3 3 in said first figure; and Fig. 4, a sectional view of the aforesaid engine on the plane indicated by line 4 4 in said first figure.

Referring by letter to the drawings, A indicates the engine-base, and B each of a pair **30** of standards on said base. Keyed or otherwise rigid in heads of the standards are pins C, having parallel offset arms D', in which the ends of a shaft D have their bearing, and an annular shell E, having a removable head **35** E', constitutes the engine-cylinder, that is provided with central outwardly-extending head-spiders terminating in collars b, loose on said pins, a power-transmitting belt-pulley F being shown in connection with one of said collars. Fast on shaft D within the cylinder are **40** annular blocks G G', that constitute sections of the engine-piston that has eccentric contact with said cylinder, the edges of said piston being beveled to match beveled surfaces in the aforesaid cylinder, as shown in Fig. 1, and thus **45** facilitate its steam-tight arrangement. An inner annular flange H of the cylinder fits space between the piston-sections G G', and thereby divides said cylinder into chambers **50** of unequal area, this flange being shown as having portions thereof separated by a radial

port c, through which steam passes from one to the other of said chambers.

Loose on shaft D and arranged to reciprocate in port c of cylinder-flange H is a slide **55** H', by which the area of said port is automatically regulated in proportion to movement of the engine when steam is passing from the cylinder-chamber of least area to that of greatest area. **60**

Guided in transverse openings in the cylinder-wall, one ahead of the other, are gates I I', each of which is preferably provided with a pivotal shoe b', that automatically adjusts itself in conformity to the face of the engine-**65** piston with which it has contact, and the port c (herein shown intermediate of terminals of cylinder-flange H) is located between the gates. Inturned ends d of gate-yokes J J' are connected to cross-heads e of pitmen K, **70** that are loose on shaft D of the engine, and these pitmen have their play between arms of the spiders that are central of the cylinder-heads.

Rotative on a stud portion of one of the **75** standard-heads is a ring L, having an inner annular groove matching a corresponding groove in the stud to provide a steam-space f in communication with a steam-inlet passage g in said standard-head. Rotative on a stud **80** portion of the other standard-head is that one of the aforesaid collars b with which pulley F has connection, and an inner annular groove of this collar matches a corresponding outer groove in the adjacent stud to form a steam-**85** space h in communication with an outlet-passage i in said stud. Ring L is connected by a pipe N with the cylinder-chamber of least area, there being a port j from steam-space f within the ring to the pipe, and the cylinder-chamber of greatest area is connected by a pipe O with a port k, leading to the annular steam-space h aforesaid. **90**

Live steam at boiler-pressure is admitted to passage g to find its way through space f, **95** port j, and pipe N to cylinder-chamber of least area, where it operates on gate I to actuate the engine, the piston of which is in steam-tight eccentric-face contact with the cylinder. The cylinder and piston having made one-**100** half of a revolution, the cylinder-chamber of least area will be full of steam, that now finds

its way through port *c* into the cylinder-chamber of greatest area, where it operates on gate *I* in the same direction as the force of initial pressure, said port being gradually opened at 5 this time by a movement of the slide *H'* in connection with the engine-shaft. The cylinder-chamber of greatest area being filled with steam, there is exhaust therefrom as the rotation of the engine continues.

10 Having thus described my invention, what I claim as new, and desire to secure by Letters Patent, is—

1. A rotary steam-engine comprising a shaft in stationary bearings, an annular shell constituting a cylinder having center bearing on stationary supports eccentric to the shaft, an annular piston in sections centered on said shaft to have steam-tight face contact with the cylinder, an annular flange in the cylinder engaging space between the piston-sections and dividing said cylinder into chambers of unequal area, portions of the flange being separated by a port; a gate arranged in each cylinder-chamber to extend through a cylinder-wall opening, the port aforesaid being between the gates, pitmen connecting the aforesaid shaft and gates, and a device that being rotative on a stationary bearing constitutes part of a steamway to cylinder-chamber of least area, provisions being had for exhaust of steam from cylinder-chamber of greatest area.

2. A rotary steam-engine comprising a shaft in stationary bearings, an annular shell constituting a cylinder having center bearing on stationary supports eccentric to the shaft, an annular piston in sections centered on said shaft, to have steam-tight face contact with the cylinder, an annular flange in the cylinder engaging space between the piston-sections and dividing the cylinder into chambers of unequal area, portions of the flange being separated by a port; means for automatically regulating area of the port in proportion to 45 movement of the engine when steam is passing from one to the other of the cylinder-chambers, a gate arranged in each cylinder-chamber to extend through a cylinder-wall opening, the port aforesaid being between the gates, pitmen connecting the aforesaid shaft and gates, and a device that being rotative on a stationary bearing constitutes part of a steamway to cylinder-chamber of least area, provision being had for exhaust of steam from 55 cylinder-chamber of greatest area.

3. A rotary steam-engine comprising a shaft in stationary bearings, an annular shell constituting a cylinder having center bearing on stationary supports eccentric to the shaft, an 60 annular piston in sections centered on said shaft, to have steam-tight face contact with the cylinder, an annular flange in the cylinder engaging space between the piston-sec-

tions and dividing the cylinder into chambers of unequal area, portions of the flange being 65 separated by a port; a port-controlling slide in connection with the aforesaid shaft; a gate arranged in each cylinder-chamber to extend through a cylinder-wall opening, the port aforesaid being between the gates, pitmen 70 connecting the aforesaid shaft and gates; and a device that being rotative on a stationary bearing constitutes part of a steamway to cylinder-chamber of least area, provision being had for exhaust of steam from cylinder-chamber of greatest area.

4. A rotary steam-engine comprising a shaft in stationary bearings, an annular shell constituting a cylinder having center bearing on stationary supports eccentric to the shaft, an 80 annular piston in sections centered on said shaft to have steam-tight face contact with the cylinder, an annular flange in the cylinder engaging space between the piston-sections and dividing said cylinder into chambers of unequal area, portions of the flange being 85 separated by a port; a gate arranged in each cylinder-chamber to extend through a cylinder-wall opening, the port aforesaid being between the gates, a piston-abutting foot 90 in pivotal connection with each gate, pitmen connecting the aforesaid shaft and gates, and a device that being rotative on a stationary bearing constitutes part of a steamway to cylinder-chamber of least area, provision being 95 had for exhaust of steam from cylinder-chamber of greatest area.

5. A rotary steam-engine comprising a shaft in stationary bearings an annular shell constituting a cylinder having center bearing on 100 stationary supports eccentric to the shaft, an annular piston in sections centered on said shaft and having bevel-edge contact with bevel surfaces in the cylinder with which it also has face contact, an annular flange in 105 the cylinder engaging space between the piston-sections and dividing said cylinder into chambers of unequal area, portions of the flange being separated by a port; a gate arranged in each cylinder-chamber to extend 110 through a cylinder-wall opening, the port aforesaid being between the gates, pitmen connecting the aforesaid shaft and gates, and a device that being rotative on a stationary bearing constitutes part of a steamway to 115 cylinder-chamber of least area, provision being had for exhaust of steam from cylinder-chamber of greatest area.

In testimony that I claim the foregoing I have hereunto set my hand, at Milwaukee, in 120 the county of Milwaukee and State of Wisconsin, in the presence of two witnesses.

SAMUEL OLSON.
